UNITED STATES PATENT OFFICE.

EDWARD POSSON, OF CHICAGO, ILLINOIS; HARRIS TRUST AND SAVINGS BANK AND EGBERT H. GOLD, EXECUTORS OF SAID EDWARD POSSON, DECEASED, ASSIGNEES TO FAY E. POSSON.

REFRIGERATOR-CAR CONSTRUCTION.

Application filed May 21, 1920. Serial No. 383,319.

This invention relates to improvements in refrigerator cars and its purpose is to provide a car of that type embodying an improved air circulating system. The invention is particularly adapted for use with the type of refrigerator car shown and described in my copending application, which has now matured into patent No. 1,399,079 dated December 6, 1921, wherein the refrigerator car is divided into refrigerant and refrigerating chambers by means of removable sectional bulkheads capable of being moved into inoperative position adjacent the roof of the car when the ice chambers are not in use. The principal object of the invention is to provide improved means for effecting a positive circulation of air through the interior of the car. A further object is to provide means operated by the movement of the car for effecting an air circulation through the refrigerant and refrigerating chambers. Still another object is to provide a ventilating device driven by the currents of air passing along the outside of the car and associated with air passages within the car for positively circulating the refrigerated air through and around the contents of the refrigerating chamber. A further feature of the invention is the provision of an improved air circulating device and an improved construction of the car for permitting the circulation of air therethrough. Other objects relate to various features of construction and arrangement which will appear more fully hereinafter.

The nature of the invention will be understood from the following specification taken with the accompanying drawings, in which one embodiment is illustrated.

In the drawings—

Figure 1 shows a top plan view of a railway car embodying the invention;

Fig. 2 shows a longitudinal sectional view on the line 2—2 of Fig. 1;

Fig. 3 shows a transverse sectional view on the line 3—3 of Fig. 1 and on the line 3—3 of Fig. 2;

Fig. 4 shows an enlarged vertical section on the line 4—4 of Fig. 1, illustrating the detailed construction of one of the air circulating devices;

Fig. 5 shows a plan view of the driving

motor of the ventilating device, the view being taken on the line 5—5 of Fig. 4;

Fig. 6 shows a top plan view of the ventilating fan within the car showing the connection of the air passages therewith, the view being taken on the line 6—6 of Fig. 4;

Fig. 7 shows a horizontal sectional view on the line 7—7 of Fig. 2, looking in the direction of the arrows; and

Fig. 8 shows an elevation of one section of the bulkhead, looking from the interior of the ice chamber.

The refrigerator car illustrated in the drawings comprises longitudinal center sills 10 and side sills 11 of metallic construction which support the wooden sill members 12 and the longitudinal side frame members 13, respectively. These frame members and the intermediate sills 14 operate in conjunction with the end sills 15 to support the floor of the car, which comprises lower floor sheathing 16 which is spaced below the floor proper, designated by the numeral 17, leaving an intermediate space 18 which may operate as an air space or may be filled with insulating material in order to prevent the entrance of heat to the interior of the car. The side walls 20 of the car extend upwardly from the side sill members 13 and from the floor 17 and these side walls comprise the outside sheathing 20^a and inside 20^b sheathing secured to the longitudinal frame members 21 and 22. The frame members 21 are wider than the frame members 22 which are secured thereto, thus leaving shoulders 23 which are adapted to form seats for the intermediate plates 24. These plates 24 may be formed of heat insulating material or of wood and they are adapted to provide intermediate air spaces between these plates and the inside and outside sheathing of the wall. The longitudinal sills 13 are provided with shoulders 13^a to co-operate with the shoulders 23 and similar shoulders 25^a are provided on the lower sides of the side plates 25 which extend longitudinally of the car along the upper boundaries of the side walls.

A plurality of transverse carlines 26 extend between the side plates 25 and support the purline plates 27. The carlines 26 and purline plates 27 support the lower roof

sheathing 28 which extends upwardly from the side plates 25 to the ridge pole 30. The upper roof boards 31 are supported by the side plates 25 and the ridge pole 30 and by 5 other longitudinal frame members 32 which are supported by the transverse bracket members 33 carried above the lower roof sheathing 28. The usual running board 34 is mounted on the roof of the car above the 10 ridge pole 30. The ceiling 35 is secured to the underside of the carlines 26 and this ceiling is cut away at the ends of the car to provide hatchways 37 which extend upwardly through the roof of the car and are 15 bounded by the frame members 38.

The floor 17 of the car supports a false floor 40 which comprises a plurality of longitudinal frame members 40^a resting on the floor and supporting the transverse floor 20 cleats 40^b which are spaced apart so that the circulation of air between the frame members 40^a and upwardly between the cleats 40^b is permitted, as illustrated by the arrows in Fig. 2. The false floor terminates 25 short of the ends of the car and the upper surface thereof is adapted to lie flush with the ice supporting platforms 42 which are located adjacent the ends of the car. These ice supporting platforms 42 comprise a plurality 30 of longitudinal frame members 43 spaced apart and having perforated metal plates 44 secured to the upper sides thereof. The frame members 43 are adapted to rest on the floor 17 which is provided adjacent 35 each end of the car with a sheet metal covering 45 forming a pan adapted to receive the water which drains from the ice in the ice chamber. This pan is recessed adjacent the end of the false floor 40 to form a transverse 40 drain channel 46. Each ice platform 42 is hinged at 42^a so that it may be swung upwardly adjacent the end wall of the car for the purpose hereinafter described.

Each end wall of the car comprises outside sheathing 47 and inside sheathing 48 supported by intermediate frame members 49. A plurality of vertical frame members 50 are secured to the inside of the inside sheathing 48 and these frame members are adapted to support a woven wire inner wall 51 so that a free circulation of air is provided from the ice chamber through the air spaces 52 between the vertical frame members 50. These air spaces 52 communicate 55 with the air spaces between the frame members 43 of the ice platforms so that the circulation of air downwardly and longitudinally of the car beneath the false floor 40 is permitted.

Each ice chamber 55 at the end of the car is separated from the intermediate refrigerating chamber 56 by means of removable bulkhead 57, which extends transversely of 60 the car and is made up of a plurality of complementary sections 58 having lugs 59

at their ends adapted to engage the slotted guideways 60 which extend vertically along the side walls. These guideways are provided with plates 61 which overlap the heads 59^a of the lugs so that the removal of the bulkhead sections from the guideways is prevented without interfering with the vertical sliding movement thereof. The vertical guideways 60 communicate at their upper ends with horizontal guideways 62 of 75 similar construction which permit the bulkhead sections to be moved into positions beneath the roof of the car when the refrigerant chambers 55 are not in use. The sliding bulkhead sections 58 are preferably of 80 solid construction except that the lower section is provided with a plurality of holes 64 to permit the passage of air from the lower part of the ice chamber. The space between the upper sliding section 58 and the roof 35 is occupied by a hinged section 65 formed of woven wire 65^a mounted on a metal frame 65^b. This hinged section is adapted to be swung upwardly and fastened 85 in a horizontal position beneath the ceiling when the bulkhead is not in use. A sheet of wire netting or a metal plate 67 is secured to the inner side of each bulkhead section 58, the sheet being attached to the bulkhead at a plurality of points 68 with the intermediate portions of the sheet bowed outwardly, as shown at 69, thus forming a plurality of 90 vertical air passages 70 which permit the downward circulation of cooled air between the ice and the solid sections of the bulkhead. 95

The intermediate portions of the bulkhead sections are supported between the side walls of the car by means of a vertical supporting member 72 in the form of an I-beam which is suspended by a bracket 73 mounted on a longitudinal track member 74. The bracket 73 extends around the track member and is adapted to engage the notches 75 and 76 which are formed in the ends of these track members. When the bracket 73 is engaging a notch 75, the lower end of the I-beam 72 is adapted to engage an aperture 77 in the ice supporting platform 42, thus maintaining the supporting member in contact with the bulkhead sections. When the bracket 73 engages the notch 76, the I-beam 72 is adapted to lie in a recess 78 which is formed between two of the vertical frame members 50 attached to the inner side of the end wall. When the supporting member 72 occupies this recess, the lower end thereof is adapted to lie behind the transverse plate 79. This plate operates in conjunction with the notch 76 to hold the supporting member 72 in its inoperative position within the end wall when the ice chamber is not in use, and particularly when the car is being used for general purposes and not as a refriger- 100 ator car. 105 110 115 120 125 130

The forced ventilation is provided by a pair of air circulating devices designated generally by the numeral 80. These devices are located on opposite sides of the running board 34 adjacent the center of the car and each device embodies a driving motor wheel 81 mounted on a vertical shaft 82. Each motor wheel is mounted above a plate or table 83 which is located in a horizontal plane and supported by the transversely extending members 84 secured to the roof 31 of the car. The motor wheel 81 comprises upper and lower circular plates 85 having a plurality of radiating vanes 86 mounted between them. These vanes have a plurality of tongues 87 formed integrally therewith along their edges and these tongues are adapted to extend through apertures 88 in the disks 85, after which they are transversely bent, as shown in Figure 5, in order to secure the parts of the wheel together. The disks 85 are secured to a central hub 89 which fits on to the tapered portion 90 of the shaft 82. The hub is secured in fixed position on the shaft by means of a nut 91 which engages the threaded extremity of the shaft. A cover plate 92 is mounted over each of the wheels 81 and these cover plates are spaced from and secured to the supporting tables 83 by means of the brackets 94 and the bolts 95. The brackets 94 are in the form of quadrants, as illustrated in Figure 5, and they are arranged diametrically opposite with their extremities located in the planes 35 of the longitudinal and transverse axes of the car, so that an intervening quadrant of the driving motor 81 is exposed to the currents of air set up by the motion of the car when it moves in either direction. These currents of air, supplemented by the natural currents of wind, will operate the motor wheel 81 and thereby rotate the shaft 82. Inclined vanes 96 are mounted between the plates 83 and 92 and are directed outwardly from the ends of the brackets 94 so that they direct the wind from either side of the car into the motor wheels.

A bushing 97 is secured to the roof 31 at the point where the shaft passes through it and this bushing is provided with a cup containing packing material 98 which prevents the entrance of moisture through the space around the shaft. Each shaft and the parts carried thereby are supported by a bearing sleeve 99 which is secured to one of the longitudinal purline plates 27 previously described. This bearing sleeve 99 is provided with an enlarged recess 100 at its upper end adapted to receive an enlarged collar or flange 101 which is formed integrally with the shaft 82. A roller bearing comprising collars 102 of angular cross-section and co-acting spherical balls 103 is mounted in the lower end of the recess 100 to coact with the annular flange 101, thereby supporting the

shaft during its rotation. The lower end of the sleeve 99 is provided with a recess 104 which supports another similar roller bearing 105 held in position by the nuts 106 engaging the lower part of the shaft. These roller bearings thus support the shaft against movement in either direction vertically. The lower tapered extremity of the shaft 82 is engaged by the hub 107 of a fan wheel 108 by which the air is circulated through the interior of the car. This hub is held in position on the shaft by a washer 109 and a nut 110 and the hub is secured to a circular disk 111. A plurality of radial vanes 112 are carried by the disk 111 on its under side and are spaced apart along their lower edges by means of an annular ring 113. The ring 113 is in the form of a flat plate and this member and the disk 111 are provided with apertures adapted to be engaged by the tongues 114 which are formed integrally with the vanes 112 and bent transversely, as shown in Figure 6.

Each ventilating fan 108 is closed in toward the side walls of the car by means of the depending walls 115 which are secured to the ceiling 35. Plates 116 are secured to the lower edges of the walls 115 and extend inwardly therefrom beneath the outer portions of the wheels 108, leaving an intervening space 117 through which air is adapted to be drawn into each wheel. The side walls 115 are of the shape illustrated in Figure 6 and are connected to the side walls of longitudinal air channels 120 which are secured to ceiling 35 and extend longitudinally therefrom, terminating somewhat short of the bulkheads 57.

The air which is drawn in by the fan wheels 108 is discharged thereby in both directions longitudinally of the car through the air channels 120. The air discharged from these channels passes through the hinged bulkhead sections 65, as illustrated by the arrows, and enters the refrigerant chambers 55. The air is cooled in these chambers and passes downwardly in the manner illustrated particularly in Figure 2, through the channels 52 which are formed between the frame members 50 and through the spaces which are formed on the inner sides of the perforated sheets 67 carried by the bulk-head sections 58. The air passing downwardly from these passageways joins the air which passes through the perforated plate 44 at the bottom of the ice chamber and this refrigerated air then circulates longitudinally of the car and passes upwardly through the false floor 40, thereby mingling with the goods contained within the storage chamber 56. The air which passes upwardly through the storage chamber is drawn in by the ventilating fans through the spaces 117 and is again circulated through the car. In this way a posi-

tive circulation of the air is maintained and this positive circulation is effected automatically by the currents of air set up by the motion of the car. When the car is adapted to be used for a general purpose car, the bulkhead sections and the supporting means therefor can be moved into position alongside of the walls and ceiling of the car, so that no part of the bulkhead construction or of the air circulating system interferes with the use of the car for general purposes.

Although I have shown and described one form of the invention for purposes of illustration, it will be understood that it may be constructed in various other ways without departing from the scope of the appended claims.

I claim:

- 20 1. The combination in a refrigerator car of a bulkhead dividing the car into refrigerant and refrigerating chambers, a metal plate secured to said bulkhead in said refrigerant chamber, and means for attaching said plate to said bulkhead at intervals, said plate being bowed outwardly from said bulkhead and provided with perforations between the points of attachment.
- 25 2. The combination in a refrigerator car of a bulkhead dividing it into refrigerant and refrigerating chambers, said bulkhead being provided with perforated air channels on the side thereof towards said refrigerant chamber, and mechanical means for causing
- 30 35 a positive circulation of air from said re-

frigerating chamber through said bulkhead and through said air channels.

3. The combination in a refrigerator car of a bulkhead extending transversely of the car and dividing it into refrigerant and refrigerating chambers, and perforated plates secured to said bulkhead sections at intervals and bowed outwardly between the points of attachment to provide air circulation channels.

4. The combination in a refrigerator car of a plurality of complementary bulkhead sections movable to a position adjacent the roof of the car, and plates secured to said sections to provide alining air channels when said sections are in bulkhead forming position.

5. The combination in a refrigerator car of a sectional bulkhead dividing the car into refrigerating and refrigerant chambers, the upper and lower sections of said bulkhead being perforated, means for permitting the movement of said sections into a position adjacent the roof of the car, and means operative when said sections are in bulkhead forming position for causing a positive circulation of air from said refrigerating chamber through said upper perforated bulkhead section to said refrigerant chamber and back through the said lower bulkhead section to said refrigerating chamber.

In testimony whereof, I have subscribed my name.

EDWARD POSSON.
